(57) **CLAIM**

The ornamental design for a game board and game pieces, as shown and described.

DESCRIPTION

FIG. 1 is a top perspective view of the game board component shown separately for clarity of illustration;

FIG. 2 is a front elevational view of the game board of FIG. 1;

FIG. 3 is a rear elevational view of the game board of FIG. 1;

FIG. 4 is a right side view of the game board of FIG. 1;

FIG. 5 is a left side view of the game board of FIG. 1;

FIG. 6 is a top view of the game board of FIG. 1;

FIG. 7 is a bottom view of the game board of FIG. 1;

FIG. 8 is a top perspective view of a game piece, shown separately for clarity of illustration;

FIG. 9 is a left side view of the game piece of FIG. 8;

FIG. 10 is a right side view of the game piece of FIG. 8;

FIG. 11 is a front elevational view of the game piece of FIG. 8;

FIG. 12 is a rear elevational view of the game piece of FIG. 8;

FIG. 13 is a top view of the game piece of FIG. 8;

FIG. 14 is a bottom view of the game piece of FIG. 8;

FIG. 15 is a top perspective view of a game piece, shown separately for clarity of illustration;

FIG. 16 is a left side view of the game piece of FIG. 15;

FIG. 17 is a right side view of the game piece of FIG. 15;

FIG. 18 is a front elevational view of the game piece of FIG. 15;

FIG. 19 is a rear elevational view of the game piece of FIG. 15;

FIG. 20 is a top view of the game piece of FIG. 15;

FIG. 21 is a bottom view of the game piece of FIG. 15;

FIG. 22 is a top perspective view of a game piece, shown separately for clarity of illustration;

FIG. 23 is a left side view of the game piece of FIG. 22;

FIG. 24 is a right side view of the game piece of FIG. 22;

FIG. 25 is a front elevational view of the game piece of FIG. 22;

FIG. 26 is a rear elevational view of the game piece of FIG. 22;

FIG. 27 is a top view of the game piece of FIG. 22;

FIG. 28 is a bottom view of the game piece of FIG. 22;

FIG. 29 is a top perspective view of a game piece, shown separately for clarity of illustration;

FIG. 30 is a left side view of the game piece of FIG. 29;
FIG. 31 is a right side view of the game piece of FIG. 29;
FIG. 32 is a front elevational view of the game piece of FIG. 29;
FIG. 33 is a rear elevational view of the game piece of FIG. 29;
FIG. 34 is a top view of the game piece of FIG. 29;
FIG. 35 is a bottom view of the game piece of FIG. 29;
FIG. 36 is a top perspective view of a game piece, shown separately for clarity of illustration;
FIG. 37 is a right side view of the game piece of FIG. 36;
FIG. 38 is a left side view of the game piece of FIG. 36;
FIG. 39 is a front elevational view of the game piece of FIG. 36;
FIG. 40 is a rear elevational view of the game piece of FIG. 36;
FIG. 41 is a top view of the game piece of FIG. 36;
FIG. 42 is a bottom view of the game piece of FIG. 36;
FIG. 43 is a top perspective view of a game piece, shown separately for clarity of illustration;
FIG. 44 is a front elevational view of the game piece of FIG. 43;
FIG. 45 is a rear elevational view of the game piece of FIG. 43;
FIG. 46 is a right side view of the game piece of FIG. 43;
FIG. 47 is a left side view of the game piece of FIG. 43;
FIG. 48 is a top view of the game piece of FIG. 43;

FIG. 49 is a bottom view of the game piece of FIG. 43;
FIG. 50 is a top perspective view of a game piece, shown separately for clarity of illustration;
FIG. 51 is a front elevational view of the game piece of FIG. 50;
FIG. 52 is a rear elevational view of the game piece of FIG. 50;
FIG. 53 is a right side view of the game piece of FIG. 50;
FIG. 54 is a left side view of the game piece of FIG. 50;
FIG. 55 is a top view of the game piece of FIG. 50;
FIG. 56 is a bottom view of the game piece of FIG. 50;
FIG. 57 is a top perspective view of a game piece, shown separately for clarity of illustration;
FIG. 58 is a front elevational view of the game piece of FIG. 57;
FIG. 59 is a rear elevational view of the game piece of FIG. 57;
FIG. 60 is a right side view of the game piece of FIG. 57;
FIG. 61 is a left side view of the game piece of FIG. 57;
FIG. 62 is a top view of the game piece of FIG. 57;
FIG. 63 is a bottom view of the game piece of FIG. 57; and,
FIG. 64 is a top perspective view of the game board and game pieces in accordance with our new design.
The evenly-dashed broken lines in the drawings illustrate the portions of the game pieces and game board that form no part of the claim.
